OTHER PUBLICATIONS

U.S. Appl. No. 61/664,383, David W. Tipton et al., "Sterilization Cassette Systems, Instrument Retention Systems for Use with a Sterilization Cassette, and Configurable Instrument Retention Members for Use Therewith", filed Jun. 26, 2012.

Primary Examiner — Anhdao Doan(74) *Attorney, Agent, or Firm* — Marshall, Gerstein & Borun LLP(57) **CLAIM**

The ornamental design for sterilization cassette, as shown and described.

DESCRIPTION

The FIGURE is a top plan view illustrating a portion of a sterilization cassette on which the ornamentation for a sterilization cassette appears.

The broken lines represent the bounds of the claim and form no part of the claimed design.
